The ornamental design for a child's vehicle, as shown and described.

DESCRIPTION

FIG. 1 is a front, left side perspective view of a child's vehicle showing our new design;

FIG. 2 is a front elevation view thereof;

FIG. 3 is a rear elevational view thereof;

FIG. 4 is a top plan view thereof;

FIG. 5 is a left side elevational view thereof, the right

side elevational view being a mirror image thereof; and,

FIG. 6 is a bottom plan view thereof.

FIG.1.

FIG.4.

FIG.5.

FIG. 6.
